UNITED STATES PATENT OFFICE

2,102,063

FLOOR SANDER

Fred L. Detwiler, Santa Ana, Calif.

Application November 25, 1935, Serial No. 51,418

1 Claim. (Cl. 51—175)

My invention relates to a floor sanding machine of the type where two or more blocks or plates are mounted side by side for reciprocatory movement and the underfaces of which plates or blocks are covered with sandpaper or the like.

The principal objects of my invention are, to generally improve upon and simplify the construction of the existing forms of similar floor sanders and to provide a sanding machine of relatively simple, durable construction which may be manufactured at comparatively low cost and which will be economical in operation and very effective in use.

Further objects of my invention are, to provide a sanding machine of the character referred to that includes a wheel supported carriage that is adapted to be moved over a floor by means of a handle, said carriage carrying an electric motor for driving the reciprocating plates that are provided on their underfaces with sandpaper; further, to provide relatively simple, strong and durable means for supporting and guiding the plates during their reciprocatory movement and further, to provide simple and efficient means for clamping the sheets of sandpaper or the like to the ends of the reciprocating plates.

A further object of my invention is, to provide a floor sander that may be conveniently employed for sanding all portions of a floor, particularly the flooring in the corners of a room or along the edges immediately adjacent the base boards, thereby eliminating the necessity of hand labor on those portions of the floor in the corners or adjacent the wall or base board.

With the foregoing and other objects in view my invention consists in certain novel features of construction and arrangements of parts that will be hereinafter more fully described and claimed and illustrated in the accompanying drawing in which:

Fig. 1 is a side elevational view of a floor sander constructed in accordance with my invention.

Fig. 2 is a top plan view.

Fig. 3 is a front elevational view.

Fig. 4 is a vertical cross section taken on the line 4—4 of Fig. 1.

Fig. 5 is a vertical cross section taken on the line 5—5 of Fig. 1; and

Fig. 6 is a detail vertical section taken on the line 6—6 of Fig. 2.

Referring by numerals to the accompanying drawing which illustrates a preferred embodiment of my invention, 10 designates a bed plate and projecting upwardly and rearwardly from the rear end thereof, is a handle 11, by means of

which the machine is moved over the floor that is being sanded. Plate 10 supports an electric motor 12, that is equipped with a cord and plug for supplying current to said motor.

Rigidly secured to the underside of the forward portion of plate 10, is a plate 13 and projecting forwardly from the sides thereof, are parallel arms 14.

Depending from the sides of plate 13, are bearings 15 for an axle 16, on which are mounted 102 small wheels 17, preferably provided with rubber tires.

Projecting upwardly from the arms 14 directly in front of plate 13, are bearings 18 for a transversely disposed crank shaft 19, which latter in 15 the present instance, is provided with two oppositely arranged cranks 20.

Secured on one end of the crank shaft 19, is a belt wheel 21 and a belt 22 connects said belt wheel with a small pulley 23 that is mounted on 20 the shaft of motor 12.

Projecting from the outer ends of the bearings 18 and surrounding the shaft journaled therein, are lugs or bushings 24, on which are loosely mounted the rear ends of forwardly projecting parallel arms 25.

The forward ends of these arms terminate above the ends of the arms 14 and said forward ends are pivotally mounted on trunnions 26 that project from the sides of vertically disposed substantially H-shaped frame 27.

The lower ends of the vertical legs of this frame rest on a transversely disposed rod 28 that connects the forward ends of the arms 14.

A second vertically disposed substantially H-shaped frame 29 is arranged between the rear portions of the arms 25 a short distance in front of the crank shaft 19 and trunnions 30 project from the sides of said frame 29 through said arms 25.

Seated in the upper and lower ends of the vertical legs of the frames 27 and 29, are longitudinally disposed parallel rods 31.

The arms 25, the upright frames 27 and 29 and the rods 31 constitute a skeleton frame for the 45 reciprocating plate carrying members hereinafter more fully described and as the rear ends of the arms 25 are journaled on the bushings 24, the entire frame may be readily swung upward with respect to the arms 14 when the sandpaper carrying plates are detached from the supporting and reciprocating means.

The ends of the legs of a pair of substantially X-shaped members 32 are provided with bearings 33 that are mounted for sliding movement upon 55

the rods 31 and pivotally connected to the central portion of each X-shaped member is the forward end of a connecting rod 34. The rear ends of these connecting rods are journaled on the 5 respective cranks 20 of crank shaft 19.

For the accommodation of the connecting rods 34, the vertical members of the H-shaped frame 29 are provided with vertically disposed slots 35.

Depending from the lowermost one of the bearings 33 on each member 32, is a lug 36 and each lug is arranged between and pivotally connected to a pair of ears 37 that are formed integral with and which project upwardly from a plate or head 38.

15 These plates which are substantially rectangular in shape, occupy positions side by side below the forward portions of arms 14 and the overall width of the two plates is slightly greater than the over-all width of the forward portion of the 20 supporting structure.

20 Formed integral with and projecting upwardly from the ends of each plate 38, are transversely disposed ribs or flanges 39 that are curved inwardly toward the center of the plate, thus 25 providing transverse pockets for the reception of the ends of the sections of sandpaper that are applied to the plate and for the rods that clamp the ends of the sandpaper to the plate.

The means employed for clamping the ends of 30 the sandpaper to the plate includes a pair of toggle structures, each comprising a short curved lever 40 that is fulcrumed between the ends of the upwardly projecting ears 37 and projecting outwardly from the end of the lever that is 35 fulcrumed to the ears, is a short arm 41. Pivotally connected to this arm, is the inward end of the outwardly projecting rod 42 and carried by the outer end of this rod is a transversely disposed rod 43 that is adapted to enter the 40 recess or groove in the corresponding flange 39 and clamp the overturned end of the sandpaper.

When the sander is equipped for use a section S of sandpaper is applied to the underface of 45 each plate 38 with the ends of said sandpaper overlying the curved flanges 39 and extending downwardly into the pockets or channels therein and by proper manipulation of the toggle members comprising the levers 40, rods 42 and rods 43, the ends of the sandpaper are firmly 50 clamped in the grooves in flanges 39 between rods 43 that are moved outwardly as the levers 40 are swung downward onto the rods 42.

In the use of my improved floor sander, handle 55 11 is manually engaged and the entire machine is moved over the floor.

60 Motor 12 through pulleys 23, 21 and belt 22 impart rotary motion to the crank shaft 19 and the connecting rods 34 that are connected to cranks 28 impart reciprocatory movement to the X-shaped frames 32. These frames reciprocate lengthwise upon the supporting rods 31 and thus the plates 38 are simultaneously reciprocated.

Due to the arrangement of the cranks 20 on the crank shaft, one plate will move forwardly while the other plate is moving rearwardly.

During operation of the machine, the handle 11 is slightly elevated so as to move the forward 5 ends of arms 14 downwardly a short distance so that rod 28 leaves the lower ends of the vertical members of frame 27 and under such conditions the entire weight of the supporting and guiding means including the arms 25, frames 27 and 29, 10 rods 31 and frames 32 is transmitted to the plates 38 so that the same exert considerable pressure upon the floor during the sanding operation.

When the machine is moved from one room to another or from one part of the room to 15 another, the handle 11 is moved downwardly to swing the forward ends of arms 14 upwardly, thereby lifting the plates 38 off the floor.

When it becomes necessary to replace the 20 sheets of sandpaper on the underfaces of the plates 38, the pins that connect the lugs 36 to ears 37 are removed and the toggles that clamp the ends of the sandpaper to the plates are released by swinging levers 40 upward.

25 Inasmuch as the reciprocating sandpaper carrying plates are slightly wider than the forward portion of the supporting structure of the machine and the forward portions of said plates project beyond the forward ends of the arms 14, the machine may be conveniently manipulated 30 so as to engage all portions of the surface of the floor and particularly at the corners of the room and in the corners between the floor and walls or base board.

Thus it will be seen that I have provided a 35 floor sander that is relatively simple in construction, inexpensive of manufacture and very effective in performing the functions for which it is intended.

It will be understood that minor changes in 40 the size, form, and construction of the various parts of my improved floor sander may be made and substituted for those herein shown and described without departing from the spirit of the invention, the scope of which is set forth in 45 the appended claim.

I claim as my invention:

In a floor sander, a wheel supported carriage, a handle projecting from the rear end of said carriage, a pair of arms projecting forwardly 50 from said carriage, a rail connecting the forward ends of said arms, a frame hinged to said carriage and positioned above said arms, the forward end of which frame normally rests on the rail that connects the forward ends of said arms, members mounted for reciprocatory movement in said frame, means on the carriage for imparting reciprocatory movement to said members, plates pivotally suspended from said reciprocating members and means on said plates for 55 clamping sheets of sandpaper thereto.

FRED L. DETWILER.
